(57) **CLAIM**

The ornamental design for a mattress cover, as shown and described.

DESCRIPTION

FIG. 1 is a top plan view of a mattress cover of the present design in accordance with a first embodiment;

FIG. 2 is a bottom plan view of the mattress cover of FIG. 1;

FIG. 3 is a front elevational view of the mattress cover of FIG. 1;

FIG. 4 is a rear elevational view of the mattress cover of FIG. 1;

FIG. 5 is a left side elevational view of the mattress cover of FIG. 1;

FIG. 6 is a right side elevational view of the mattress cover of FIG. 1;

FIG. 7 is a perspective view of the mattress cover of FIG. 1;

FIG. 8 is a top plan view of a mattress cover of the present design in accordance with another a second embodiment;

FIG. 9 is a bottom plan view of the mattress cover of FIG. 8;

FIG. 10 is a front elevational view of the mattress cover of FIG. 8;

FIG. 11 is a rear elevational view of the mattress cover of FIG. 8;

FIG. 12 is a left side elevational view of the mattress cover of FIG. 8;

FIG. 13 is a right side elevational view of the mattress cover of FIG. 8;

FIG. 14 is a perspective view of the mattress cover of FIG. 8; and

FIG. 15 is a top plan view of a mattress cover of the present design in accordance with a third embodiment;

FIG. 16 is a top plan view of a mattress cover of the present design in accordance with a fourth embodiment;

FIG. 17 is a bottom plan view of the mattress cover of FIG. 16;

(Continued)

FIG. 18 is a front elevational view of the mattress cover of FIG. 16;
 FIG. 19 is a rear elevational view of the mattress cover of FIG. 16;
 FIG. 20 is a left side elevational view of the mattress cover of FIG. 16;
 FIG. 21 is a right side elevational view of the mattress cover of FIG. 16;
 FIG. 22 is a perspective view of the mattress cover of FIG. 16;
 FIG. 23 is a top plan view of a mattress cover of the present design in accordance with a fifth embodiment;
 FIG. 24 is a bottom plan view of the mattress cover of FIG. 23;
 FIG. 25 is a front elevational view of the mattress cover of FIG. 23;
 FIG. 26 is a rear elevational view of the mattress cover of FIG. 23;
 FIG. 27 is a left side elevational view of the mattress cover of FIG. 23;
 FIG. 28 is a right side elevational view of the mattress cover of FIG. 23;
 FIG. 29 is a perspective view of the mattress cover of FIG. 23; and,
 FIG. 30 is a top plan view of a mattress cover of the present design in accordance with a sixth embodiment.
 The broken lines shown in the drawings illustrate portions of the mattress cover that form no part of the claimed design.
